C. ZIMMERMAN

BRIDGE

Filed Jan. 28, 1926

UNITED STATES PATENT OFFICE.

CASPER ZIMMERMAN, OF FORT COLLINS, COLORADO.

BRIDGE.

Application filed January 28, 1926. Serial No. 84,390.

This invention relates to bridges and more particularly to the method of constructing wooden bridges.

An important object of the invention is to produce a wooden bridge structure which is capable of being substantially completely protected from the elements by sheathing with light sheet metal or similar material.

A further object of the invention is to provide a device of this character which may be readily and cheaply produced and installed, which will be durable and efficient in service and a general improvement in the art.

15 These and other objects I attain by the construction shown in the accompanying drawing, wherein for the purpose of illustration is shown a preferred embodiment of my invention and wherein:—

20 Figure 1 is a side elevation of a bridge truss constructed in accordance with my invention, the covering being removed;

Figure 2 is a longitudinal sectional view therethrough;

25 Figure 3 is a section on the line 3—3 of Figure 2.

Referring now more particularly to the drawings, the numeral 10 generally designates truss members, each in the form of a compound truss consisting of a main truss 11 and a lesser or reinforcing truss 12 having a common base 13. The truss 11 includes the usual upper member 14 connected with the base member by inclined end members

30 15. The truss 12 includes an upper member 16 of considerably less length than the upper member 14 of the main truss and abutting the under surface of the member 14 at the center thereof. From the ends of this upper member, inclined end members 17 extend downwardly to the base and these inclined end members preferably parallel the end members 15 of the main truss.

40 A pair of the trusses 10 are provided, these trusses being connected by cross beams 18. Of these cross members, the central cross member is connected with the upper ends of the end members 17 of the inner truss by turn-buckle rods 19 extending through the base member 13. The remaining cross beams are connected to the upper member 14 of the main truss by vertical rods 20 extending through the upper and base members of the main truss and provided with nuts whereby 45 50 55 they may be adjusted to draw the beams

against the lower surface of the base member 13.

It will be noted that the lower ends of the end members 17 of the inner truss substantially vertically align with the upper ends of the end members 15 of the main truss and of the beams 18. Certain of the beams are arranged so that they immediately underlie the lower ends of the end members 17 so that the vertical member 20 associated therewith serves to tension the end members 15 and 17 and provide a diagonal for the parallelogram described by the base 13, upper member 14 and end members 15 and 17. Others of the cross beams are arranged vertically below the upper ends of the cross member 17 of the inner truss.

It will at once be obvious that a structure of this character will be very rigid and is comparatively free from the usual cantilever effect which causes bowing at the central portion of the bridge structure. The weight at the center of the base member 13 is transmitted to the upper ends of the end members 17 of the inner truss and is in turn transmitted by these end members to the base member at points adjacent the ends thereof where the cantilever effect meets with much greater resistance. Furthermore, the upper member 14 of the bridge structure which serves to provide the actual support, is securely braced from its lower member from points adjacent the ends thereof. The structure thus provided is completely sheathed, as indicated at 21, and the cross beams 18 are likewise completely sheathed before they are placed in position. Upon these cross beams may be laid the usual stringers 23 serving as a support for transversely extending flooring 25. Before the flooring is applied, a sheet metal covering is applied to the upper surface of the ends thereof, as at 26, and this covering is continued upon the ends and below the flooring a sufficient distance to extend to the upper surface of the beams 18. This provides protection not only for the ends of the flooring but for the sides of the stringers 23. Upon the structure thus provided, between the trusses 10, a layer of asphalt is laid, as indicated at 27.

It will be seen that little, if any, of the wooden structure of the bridge is subjected to the action of the element as in event the asphalt covering fails to make a proper

joint with the trusses 10, the metal strips 26 will prevent any damage to the floor boards or stringers. It will also be obvious that a bridge of this character may be very readily and cheaply produced and installed and will be durable and efficient in service.

It will also be obvious that the construction hereinbefore set forth is obviously capable of a certain range of change and modification without materially departing from the spirit of the invention and I accordingly do not limit myself to such specific structure except as hereinafter claimed.

15 I claim:—
15 The combination in a wooden bridge hav-

ing truss members, of cross beams connecting said trusses and likewise having a metallic sheathing, stringers upon said cross beams, a flooring upon the stringers, a metallic covering for the outer ends of the upper surface of the flooring, said metallic covering extending downwardly at the ends of the flooring and between the truss members and the stringers and an asphalt covering for said flooring between said truss members 25 having sealing engagement with the sheathing of the truss at its edges.

In testimony whereof I hereunto affix my signature.

CASPER ZIMMERMAN.
